UNITED STATES PATENT OFFICE.

FRANK MILLER, OF LOS ANGELES, CALIFORNIA, ASSIGNOR OF ONE-HALF TO TONY ANTHONY BARBER, OF LOS ANGELES, CALIFORNIA.

SOUND REPRODUCER.

Application filed August 17, 1927. Serial No. 213,514.

My invention is a sound reproducer of the phonograph type reproducing sound by the vibration of a needle due to the action of a disc with sound recorded thereon.

5 My invention has several objects such as improvements in the amplifier horn and in a sound amplifier mounted internally of the horn.

10 The amplifying horn is constructed of wood and is made substantially pyramidal in shape with the apex adjacent the connection to the tone arm. In the horn I mount a sound amplifier which has a relatively small tube extending lengthwise of the horn, and a 15 bell end on the tube which is covered by a perforated cap. Surrounding this cap I have a disc of wood, and outside of the wood there is a cover plate. On the tube connected to two bridges I have a number of copper 20 wires strung which are under tension, thereby forming vibrating wires.

25 The effect of the amplifier in the horn is that it appears to form a resonance chamber, and is constructed of a material which readily takes up vibration, and this, with the disc made preferably of gum wood, gives a vibrating element in the horn which greatly amplifies the sound. The wires strung tightly under tension on the tube of the amplifier 30 appear to set up vibrations and to affect the amplifying of the sound.

My invention is illustrated in the accompanying drawings, in which:

Figure 1 is a longitudinal section of my 35 sound reproducer taken substantially on the line 1—1 of Figure 3 in the direction of the arrows.

Figure 2 is a vertical transverse section taken on the line 2—2 of Figure 1 or Figure 40 4 in the direction of the arrows, looking into the horn and at the face of the amplifier.

Figure 3 is a horizontal section taken substantially on the line 3—3 of Figure 1 or 4 in the direction of the arrows.

45 Figure 4 is a vertical longitudinal section taken on the line 4—4 of Figure 2 in the direction of the arrows.

Figure 5 is a vertical transverse section of Figure 4 showing in detail the horn and 50 amplifier.

The horn is constructed substantially as follows, having reference particularly to Figures 1 through 5. The horn has a back sup-

porting strut 40 which is supported on the floor 41 of the cabinet. There is a lower 55 board 42 which extends from the support 40 to the front 43 of the cabinet. The upper board 44 extends from the front of the cabinet from the back 45, and there are two vertical side boards 46. The meeting edges 47 60 of these various boards converge towards the inner end 48, this being substantially the apex of a pyramid with steep sides, the base of the pyramid being reached by the open front of the cabinet. This horn has an opening 50 adjacent its inner end for receiving the lower part 50' of the tone arm. The horn is preferably constructed of wood of the character to give a free and good vibration.

70 My sound amplified built into the horn is constructed substantially as follows, this being illustrated particularly in Figures 1 through 5. The amplifier is designated generally by the numeral 55 and comprises a 75 small tube 56 having an open inner end 57. This tube enlarges into a bell 58 which has a flange 59. A cover 60 is welded at the end of the bell inside of the flange and has an internal and depressed central section 61. 80 There are a series of perforations 62 through this cover 60. A disc 63 formed of wood (preferably gum wood) is secured to the flange 59 by small screws or the like. This disc is illustrated in Figure 2 and is preferably hexagonal on its periphery. The cover plate 65 is secured by countersunk screws 66 to the wood disc 63, there being metal sleeves 67 surrounding the screws. This cover plate has a series of perforations 68 and an 85 outwardly curved central section 69. The wooden disc is centered in the horn by means of lower and upper centering screws 70 and 71.

The inner end of the tube 56 has a bridge 95 72 in the form of a flat ring which engages the sides of the pyramidal-shaped horn. There is another bridge 73 secured to the bell 58 by soldering or the like, this bridge also being in the form of a flat ring. These 100 bridges are connected by a series of tightly drawn wires 74.

In constructing the sound amplifier, I 105 preferably construct a tube 56 of copper and also the bell of copper. The cover 60 is preferably formed of brass. The disc 63 is

preferably of gum wood. The cover plate 65 may be formed of aluminum. The bridges 72 and 73 are formed of brass, and the wires 74 of plated copper, these wires being drawn 5 under a fairly high tension.

Various changes may be made in the principles of my invention without departing from the spirit thereof, as set forth in the description, drawings and claims.

10 I claim:

1. In a sound reproducer, a horn having a sound amplifier built therein, said amplifier having a small tubular end at the inner part of the horn and a belled part towards 15 the outer end of the horn, a pair of ring-like bridges secured to the small end of the horn and to the bell, and tightly stretched wires between the said bridges.

2. In a sound reproducer, a horn having a sound amplifier built therein, said amplifier having a small inner end substantially cylindrical enlarging into a bell, the bell having a 20 perforated outwardly curved cover, bridges secured to the inner end of the ring and to 25 the bell, and tightly drawn wires connecting the said bridges.

3. In a sound reproducer, as claimed in claim 2, the cover of the bell having a depressed central section pressed inwardly, the

perforations surrounding the inwardly 30 pressed section.

4. In a sound reproducer having a horn formed of wood and of pyramidal internal shape with the apex connected to a tone arm, a sound amplifier built in the horn comprising 35 a small tubular end substantially cylindrical adjacent the apex of the horn, a belled enlargement of the tube having a perforated outwardly curved cover secured to the end of the bell, a ring of wood secured to the 40 cover, and a perforated cover plate secured to the ring of wood and spaced therefrom, said cover plate being spaced also from the cover of the bell.

5. In a sound reproducer, a horn having a sound amplifier built therein, said amplifier having a small tube at the inner end, a bell forming an extension of said tube, an outwardly curved cover with perforations secured to the bell, a perforated cover plate 50 secured in front of the cover, the cover of the bell having a ring of wood secured thereto, and the cover plate being attached to the wood ring and spaced therefrom.

In testimony whereof I have signed my 55 name to this specification.

FRANK MILLER.
